UNITED STATES PATENT OFFICE.

MICHAEL SCHULTES, OF YOUNGSTOWN, OHIO, ASSIGNOR OF ONE-THIRD
TO JAMES H. CLARKIN, OF YOUNGSTOWN, OHIO.

METALLIC CURTAIN.

No. 830,456.

Specification of Letters Patent.

Patented Sept. 4, 1906.

Application filed January 19, 1906. Serial No. 296,911.

To all whom it may concern:

Be it known that I, MICHAEL SCHULTES, a citizen of the United States, residing at Youngstown, in the county of Mahoning and State of Ohio, have invented a new and useful Metallic Curtain, of which the following is a specification.

This invention relates to flexible curtains for desks, cabinets, fireproof blinds, stage-curtains, cases, and like structures, and has for its principal object to provide a flexible metallic curtain in which the joints will be water, fire, and dust proof to the extent of preventing the accumulation of dust and dirt between the members of the curtain, as well as preventing the passage of water, fire, or dust to the interior of the desk or other structure to which the curtain is applied.

A further object of the invention is to provide a device of this character in which the joint members are of such construction as to form rigid braces or supports for strengthening the several sections or braces of the curtain and in which the area of the sections in frictional contact is reduced to a minimum in order to prevent the free flexing of the curtain as it is moved to open and closed positions.

A still further object of the invention is to provide a metallic curtain in which the outer or exposed surface will be smooth and continuous whether the curtain is arranged on a straight or curved line.

A still further object of the invention is to provide a curtain of this class with means for protecting it from wear and injury, more especially at the end portions of the metallic strips of which the curtain is composed.

A further object of the invention is to provide end protective members which shall take up all of the wear incident to the sliding of the curtain in the guiding-grooves of the desk, case, or other structure.

A still further object of the invention is to provide a metallic curtain in which the ends of the strips are reinforced by links so connected as to permit free flexing of the curtain to follow the curvatures of the grooves.

With these and other objects in view, as will more fully hereinafter appear, the invention consists in certain novel features of construction and arrangement of parts, hereinafter fully described, illustrated in the accompanying drawings, and particularly

pointed out in the appended claims, it being understood that various changes in the form, proportions, size, and minor details of the structure may be made without departing from the spirit or sacrificing any of the advantages of the invention.

In the accompanying drawings, Figure 1 is a perspective view of a portion of a flexible curtain constructed in accordance with the invention. Fig. 2 is a plan view of the metallic links which are attached to the ends of the curtain-strips, a number of links being shown connected together. Fig. 3 is a detail perspective view of one of the links detached. Fig. 4 is a view similar to Fig. 3, illustrating a link stamped of sheet metal. Fig. 5 is a sectional elevation of a curtain, showing the same as applied to a desk of ordinary construction. Fig. 6 is a sectional view of a number of the members of the curtain drawn to an enlarged scale. Fig. 7 is a detail perspective view of one of the members or sections detached. Fig. 8 is a similar view showing a curtain formed of sheet metal on which a suitable design has been stamped. Fig. 9 illustrates a slightly-modified construction of the curtain. Fig. 10 illustrates a further modification of the curtain.

Similar numerals of reference are employed to indicate corresponding parts throughout the several figures of the drawings.

Each of the members or sections 10 is formed of a strip of sheet metal of any desired gage, and one edge of the strip is provided with a flange 11 and the other with a 90 rolled bead 12, the flange of one section fitting within the bead of an adjacent section and permitting free flexing of the curtain as a whole.

The rib 11 is approximately sigmoidal in cross-section, and at its juncture with the flat outer face 13 of the strip there is formed a small depression or recess 14, which receives a sharply-defined rib 15, formed at the beaded edge of the next section.

The bead 12 is approximately circular in cross-section, its outer edge being continued up and turned to form a flange 16, that is slightly spaced from a curved or recessed portion 17, that connects the rib 15 to the main portion of the bead 12, the curvature of the portion 17 being approximately on a line concentric to the curvature of the flanged edge

16 and the space between the two serving for the entrance of the upper portion of the rib 11 of an adjacent section.

The various sections can be assembled only by sliding endwise one upon the other, and when so assembled a hinge is formed between each two sections, but the frictional surface of said hinge is very limited, comprising only a portion of the flanged edge 16 and a portion of the rib 11, so that the several sections may swing freely one on the other to permit the curtain to follow a guide of any contour.

When the sections are assembled, the outer surfaces 13 present a smooth continuous face, the ribs 15 being seated in the recesses 14 and preventing any movement in one direction beyond a straight line, while permitting the utmost freedom of movement in the opposite direction.

Inasmuch as the upper portion of the rib 11 fits snugly between the two approximately parallel or concentric portions 16 and 17, dust and dirt will be excluded and there will be no danger of accumulations within the beads 12, nor is it possible for any dust or dirt to pass between the sections into the desk proper.

It is obvious that by limiting the area of surfaces in frictional contact and forming the hinge-joint proper adjacent to the outer surface of the curtain free flexing will be permitted and the curtain may be readily adjusted to open or closed positions.

In Fig. 9 is illustrated a slightly-modified construction, the parts remaining the same as previously described with the exception that the recess 14 is omitted.

In the construction shown in Fig. 10 one edge of each strip 10 is bent inwardly at an acute angle to the plane of the strip, as indicated at 11', and is thence bent on a reverse curve forming a tongue 12'. The opposite edge of the strip is bent inwardly at an obtuse angle to the plane of the strip, as indicated at 13', in order that it may be parallel with and make close contact with the inwardly-bent portion 11 of an adjacent strip. From thence the metal is arranged on a curved line following the upper portion of the curved tongue 12' and thence is bent to form a practically complete loop 14', the upper edge of which is turned to form a bead 15', that rests within the concaved portion of the tongue 12'. It will be seen that that portion of the tongue 12' adjacent to the body of the strip is arranged to play between two curved portions of an adjacent strip, and while a joint is so made the curtain may be readily flexed to follow the different curvatures of the guiding-grooves in which the edges of the curtain are received. The joint formed will be sufficiently tight, especially when the outer faces of the strips are all in the same plane to positively exclude moisture, snow, or dust.

In many curtains of this general type it has been usual to place the ends of the strip within guiding-grooves without any additional protection against wear, and a sliding friction, especially on heavy curtains, will in time wear through the metal of the strips and render the curtain useless. At the same time the ends of the curtain are exposed to constant danger of injury and displacement, especially where a portion of the end of the curtain may slip out of or be arranged to extend below the groove. In order to overcome this objection, the ends of the strips are provided with links 20 of the character best shown in Fig. 3.

Each link 20 is provided with a laterally-projecting belt 21, that is riveted or otherwise secured to the inner face of the strip 10. The link proper is in the form of a bar having one end 22 in a plane somewhat beyond but parallel with the plane of the opposite end 23, so that the ends of adjacent links may interfit and their inner faces all be in contact with the ends of the metallic strips which make up the curtain. The ends of the links are united by studs 24, which may be rigidly secured in openings 25 at the ends 23 of the links, but are free to play in arcuate grooves 26 at the ends 22 of said links. This permits free flexing of the curtain, so that it may follow a guiding-groove having any curvature.

Each link is provided with an outwardly-extending curved rib 27, that is arranged to engage against the bottom wall of the guiding-groove and presents but a comparatively small frictional surface, so that there will be little, if any, wear on the links, and there will be no strain whatever on the strips 10. These ribs 27 may be made of such width as to permit the use of the curtain for a practically indefinite period, and when worn out the links may be replaced at comparatively small cost. This may also be accomplished by the employment of a detachable rib 27', as shown in Fig. 4.

In the construction shown in Fig. 4 the link is made of two pieces of stamped sheet metal, one of which forms the body of the link and the securing-tongue, while the second member forms the rib. The body of the link is provided with openings 30 for the passage of small lugs formed at the inner face or edge of the rib, and these lugs may afterward be upset in order to firmly hold the rib in place. When formed of sheet metal, one end of the link may be struck up to form a headed pin 24', that is integral with the body of the link and may be passed through the elongated opening 26 of an adjacent link.

With a device constructed in accordance with this invention the life of the curtain is materially increased, and the curtain may be more readily operated, owing to the reduced area of the surfaces in frictional contact.

I claim—

1. A curtain of the class described having wear-links at its opposite ends.
  2. In a flexible metallic curtain, links secured to the ends of the strips.
  3. In a flexible metallic curtain, a series of connected links arranged at the edge of the curtain, and means for securing the links to the curtain-strips.
  4. In a flexible metallic curtain, links secured to the ends of the curtain-strips and provided with ribs forming reduced friction-surfaces for engagement with the walls of the curtain-guiding grooves.
  5. In a metallic curtain, wear-links connected to the ends of the curtain-strips and having pin-and-slot connections with each other.
  6. In a metallic curtain, a link secured to the end of each strip, one end of each link being bent outward to permit overlapping of the several links.
  7. In a metallic curtain, a link arranged at the end of each curtain-strip and provided with an inwardly-extended flange secured to the strip, and an outwardly-extended rib for contact with the bottom wall of the curtain-guiding groove.
  8. In a metallic curtain, a plurality of strips each bent at one edge at an acute angle and at the opposite edge at an obtuse angle to form moisture-excluding joints, the edges being further bent to form a hinge.
  9. A metallic curtain formed of a plurality of sections, each section having at one edge a rib, and at the opposite edge a bead, the inner portion of the bead being of sufficient diameter to permit free play of the inner portion of the rib, the edges of the bead being brought into parallel relation close to the outer face of the curtain, and forming friction-surfaces of reduced area for contact with a portion of the rib.
  10. A metallic curtain having a flat outer face, and comprising a plurality of parallel sections having interengaging edge portions, one provided with a rib, and the other with a bead, the edges of the latter being brought into parallel relation and being disposed on curved lines, that portion of the rib which fits between such faces being also curved, the ribbed edge being recessed, and the beaded edge having a well-defined shoulder fitting in said recess to limit flexing movement of the curtain in one direction.
  11. A metallic curtain formed of a plurality of parallel sections, each provided at one edge with a rib of approximately sigmoidal form in cross-section and at the opposite edge with a bead, the edge portion of the bead being flanged, and seated within one of the curved portions of the rib of the adjacent section.
  12. A metallic curtain formed of a plurality of interengaging sections each having at one edge a rib of approximately sigmoidal form in cross-section, and at the opposite edge a bead of approximately circular form in cross-section and adapted for the reception of the rib, the adjacent spaced walls of the rib being arranged on approximately concentric lines and affording a curved passage for the rib of an adjacent section.
- In testimony that I claim the foregoing as my own I have hereto affixed my signature in the presence of two witnesses.
